Letters Patent No. 1919 Dated March 8th 1864.

Design for a Carpet Pattern.

The schedule referred to in these Letters Patent and making part of the earn

To all whom it may concern:

It is known that I, Henry G. Thompson, of the City, County and State of New York, have invented or produced a new and original Design for a Pattern to be wrought into three ply Degrain and other carpeting in colors similar to those painted on the drawings accompanying this specification, or in other colors substituted in the place of those painted on the drawings herewith: and do hereby declare that the drawings accompanying this specification do give and convey to any one skilled in the art of carpet weaving a more defined and thorough description of the nature of my invention than it is in the power of language otherwise to convey, and is sufficient to enable any one skilled in the art of carpet weaving to use my invention.

What I claim as my invention, and desire to secure by Letters Patent, is the configuration of the design herein-to annexed, when made by being wrought into three ply Degrain or other carpeting, in the form similar to the drawings accompanying this specification.
